DESIGN FOR A GARTER

Isaiah A. Botty, New York, N. Y.

Application August 14, 1933, Serial No. 49,024

Term of patent 7 years

To all whom it may concern:

Be it known that I, ISAIAH A. BOTTY, a citizen of the Republic of Argentine, residing at New York city, in the county of New York and State of New York, have invented a new, original, and ornamental Design for Garters, of which the following is a specification, reference being had to the accompanying drawing, forming part thereof.

Fig. 1 is a face view of a garter showing my new design.

Fig. 2 is an enlarged perspective view of one end of the garter.

Fig. 3 is an enlarged perspective view of the other end of the same.

I claim:

The ornamental design for a garter as shown.
ISAIAH A. BOTTY.
